United States Patent Office.

HENRI E. BISSELL, OF HARTFORD, CONNECTICUT.

Letters Patent No. 94,701, dated September 14, 1869.

IMPROVED SPRING BED-BOTTOM.

The Schedule referred to in these Letters Patent and making part of the same.

To all whom it may concern:

Be it known that I, HENRI E. BISSELL, of Hartford, in the county of Hartford, and State of Connecticut, have invented a new and useful Improvement in Spring-Beds; and I declare the following to be a full and exact description thereof, reference being had to the accompanying drawings, and to the letters of reference marked thereon, forming a part of this specification.

Figure 1 is a plan view of my invention.

Figure 2 is a view of the bottom of the bed.

Figure 3 is a sectional view of the "tightening-apparatus," situated at the foot of the bed.

Figure 4 is a detached view of one of the sockets for the ends of what is known herein as the "head-piece."

Figure 5 is a detached view of the socket for one of the ends of the "foot-piece."

Figure 6 is a detached view of the socket for the other of the ends of the "foot-piece."

The letters *a a a* designate the three sections of which the bed is composed, which sections are made of stout canvas, or of some equivalent therefor.

If the whole bed were made in one piece, when two persons made use of it, they would both roll into the middle together, while, by making the bed in sections, I avoid this difficulty altogether.

The sections are laced somewhat loosely together by strings running through eyelet-holes.

At the head of the bed is a stout bar, of wood, *b*, called a "head-piece" herein, each end of which fits down into the sockets *c*, shown in fig. 4, which sockets are fixed to the inside of the two side pieces, *d* and *d*, of the bed.

These sockets can just as well be made into the side pieces, but I think a metal socket, screwed to the side, is preferable.

It will be readily understood that the "head-piece" *b* is removable at pleasure from the sockets.

The sections *a* are attached to the head-piece *b*, each by means of two short bars of metal, made into a ring at one end, which is stoutly fastened to one

end of the section. Each of these bars runs into the "head-piece," and through a spiral spring, or its equivalent, and is attached to the back of the spring, which spring is contained in a proper socket in the "head-piece," and the other end of the spring from that to which said bars is attached, rests against the bottom of the socket. This arrangement, so far as concerns one of the springs, is represented at *e*.

At the foot of the bed, the sections run over the "foot-piece" *i*, down under the bed. This foot-piece is a sort of a cam or eccentric, the bearings of which rest in the sockets *h* and *h'*, and from the shape of *h'* it will readily be understood that the foot-piece, as well as the head-piece, is removable at pleasure.

These sockets, *h* and *h'*, are screwed to the insides of the side-pieces of the bed, *d d*.

The sections come to an end shortly after passing around the cam *i*. To these ends are attached the strainers *k k k*, which are buckled at their other ends to the bottoms of the sections, and by means of these strainers any desired tension can be given to the sections.

It is also desirable to tack the sections to the bottom of the cam *i*, as by the tacks, *o o o o o*, shown, and then when the strainers are buckled tighter, the action of the cam will also assist in straining the sections.

A roller and ratchet can be substituted for the cam, but I think the cam preferable.

I claim as my invention—

The webbing-bottom, made in sections, laced together as described, in combination with the strainers *k k k*, the movable head-piece *b*, with its sockets, springs, and bars, and the cam *i*, the whole arranged and constructed as described, for the purpose set forth.

Dated July 3, 1869.

H. E. BISSELL.
